UNITED STATES PATENT OFFICE.

EDWARD C. TERRY, OF HARTFORD, CONNECTICUT.

PISTON WATER-METER.

SPECIFICATION forming part of Letters Patent No. 355,037, dated December 28, 1886.

Application filed January 4, 1886. Serial No. 187,588. (No model.)

To all whom it may concern:

Be it known that I, EDWARD C. TERRY, a citizen of the United States, residing at Hartford, in the county of Hartford and State of Connecticut, have invented certain new and useful Improvements in Water-Meters, of which the following is a specification.

My invention relates to improvements in water-meters of the class known as "piston-meters;" and the object of my invention is to prevent the pistons from hammering against the case.

In the accompanying drawings, Figure 1 is a longitudinal section of my meter, partly in elevation. Fig. 2 is a transverse section, partly in elevation, of the same, less the side cap, the plane of section being indicated by the line $x\ x$, Fig. 1. Fig. 3 is a longitudinal section of the case. Fig. 4 is a perspective view of one of the pistons, and Figs. 5 and 6 are diagrams of the two pistons and the various ports or valves on that side of the pistons which face the part of the case illustrated in Fig. 3.

25 A designates the main body of the case, in which I form two cylindrical piston-chambers, the ends of which are covered by caps B B. An opening is formed at one side of the case A for the introduction of a frame, E, within 30 which the crank-shaft a is mounted. This opening is to be covered by a side cap, as indicated by broken lines in Fig. 2, and in this cap the registering mechanism may be placed. The cranks b of the shaft a engage suitable 35 slots in the body of the respective pistons, and thereby determine their stroke.

D designates the threaded neck for connection with the inlet-pipe, and C a like neck for connection with the outlet-pipe. A passage 40 leads from the inlet-pipe through one side of the case to the inlet-ports 1 and 2 in the piston-chambers, as indicated by broken lines in Fig. 3. Other passages through one side of the case connect the two piston-chambers and 45 lead to the ports 3 and 4, 5 and 6, 7 and 8, and 9 and 10, respectively, all as indicated by broken lines in Fig. 3. Each piston has upon the side which faces these ports two depressions and three openings. The depressions 50 are oblong, and serve to connect temporarily the ports of the case without letting water

through the shell of the pistons while the openings let water through said shell, and, with the exception of openings 11 and 12, let the water into the body of the pistons, 55 from whence it passes to the outlet. These openings and depressions, or "valves," as they are sometimes called, are designated in Figs. 5 and 6 by the figures 11 to 20, inclusive, the odd numbers being used here and 60 in Fig. 3 for one side of the meter and the even numbers for the other side.

When the pistons are in certain positions, the depression 15 connects the ports 1 and 5. Depression 17 connects the ports 1 and 7. 65 The opening 11 registers with the port 3, 13 with 5, and 19 with 7. The depression 16 connects the ports 2 and 4. Depression 18 connects the ports 2 and 10. The opening 12 registers with the port 6, 14 with 4, and 20 with 70 10. There are two piston-chambers, and when the pistons are placed therein there are four measuring-chambers, one at each end of each piston.

The major portion of my meter being old I 75 consider it unnecessary, after thus pointing out the various passages and ports, to explain in detail the flow of water through the machine or the mode of operation of the entire machine, as it is substantially the same as others, except 80 that I cut off the flow of water from and to one end of each piston in such manner as to stop the pistons before they strike the caps, or at least to prevent them from striking the caps with any considerable force. I accomplish 85 this result by forming the openings 11 and 12 through the shell of the pistons, leaving a solid portion on each side of said openings, which portions act alternately to open and close the ports 3 and 6; and I also form a pas- 90 sage, 21 and 22, from these openings 11 and 12 to the extreme ends of the piston, as shown in Figs. 1 and 4. These openings have the effect to divide the piston end, or that face of the piston which is opposed to and forms one wall 95 of the measuring-chamber, a part of said face being at the literal or extreme end of the piston, and a part of it being at the end of the passage 21 or 22. By this construction the passages leading from one piston-chamber to 100 the other and terminating in the ports 3 and 6 lead to the operative piston end when the pis-

ton is near the end of its stroke, so that said passage opens into the measuring-chamber at the end of the piston, as shown in Fig. 1. When the opening 11 in the piston registers 5 with the port 3 of one measuring-chamber, the piston on the other side of the meter will be in a position to have the depression 16 connect the ports 2 and 4, so that water will be admitted through the ports 3 and 11 and pass 10 sage 21 to the end of the piston, and consequently will move that piston toward the other end of the piston-chamber. Just before the piston reaches that end the solid portion of the piston-shell by that side of the opening 15 11 which is nearest this end of said piston covers up the port 3 and cuts off the supply of water, and consequently the piston will stop without thumping the cap. Upon the return of this piston the opening 14 of the opposite 20 piston (which opening leads to the outlet) registers with the port 4, so that water may flow out through the opening 11 and port 3 and empty the measuring-chamber at that end of the piston-chamber as the piston returns. 25 Just before the piston completes its stroke the solid part of the piston-shell on the other side of this opening 11 (the side which is farthest from this end of said piston) covers the port 3, so as to cut off the exit of water from that 30 end of the piston-chamber, and consequently the piston will stop without thumping. The opening 12 of the other piston operates in like manner in connection with the ports 6, 5, and 1, depression 15, and opening 13. The solid 35 portion of each piston-shell, in connection with the ports 3 and 6, acts as a valve to cover and uncover said ports, and for convenience I will designate the portions of the pistons which so act as the "cut-off valve."

40 The water is admitted to and from the opposite ends of the pistons by ports 7, 8, 9, 10, 1, and 2, depressions 17 and 18, and openings 19 and 20; but the ports 8 and 9 are never closed by the action of the pistons. This is 45 substantially the ordinary construction. While it is necessary to employ only one cut-off valve in each piston when that valve operates to both cut off the supply and discharge from and to one end of each piston-chamber, the 50 same result may be attained by providing each piston with two cut-off valves, each acting one way only—that is, both valves acting to cut off the discharge from both ends of its own piston-chamber, or to cut off the supply to 55 both ends of its own piston-chamber, and a piston having two such valves acting to cut off the water in its own piston-chamber I consider the full equivalent of a single cut-off acting in a double capacity, as before stated.

60 By reference to Fig. 3 it will be seen that the ports of two measuring-chambers—viz., the ports 3 and 6—are located within that portion of the cylindrical walls which is traversed by the respective pistons, while the ports of the 65 other two measuring-chambers—viz., the ports 8 and 9—are located outside of that portion of the cylindrical walls which is traversed by the

pistons, the former embodying my improvement and the latter being old. If that portion of the piston-shell which is between the ports 11 and 12 and the end of the piston nearest thereto were removed, then the piston-shell would cover the ports 3 and 6 when moving one way only, and consequently the piston-shell would act only to cut off the flow of water from the measuring-chamber at that end of the piston; and this is what is meant by a cut-off valve acting one way only. In such a case the ports of all the measuring-chambers would have to be located within that portion of the cylindrical wall which is traversed by the piston; but by the specific construction shown it is only necessary to locate the ports of two of the measuring-chambers in the path traversed by the piston. In order to determine the stroke 85 of the pistons and make the meter an operative one, the shaft and cranks, or some equivalent mechanism, must be employed. While I have described the piston-shell as covering the ports 3 and 6, it does not close them absolutely water-tight, but substantially covers them, so as to practically, but not absolutely, cut off the supply and discharge and thereby prevent thumping. There should always be a very slight opening or leakage when the piston is at the end of its stroke, in order to start the piston on its return.

By my construction I prevent the thumping or hammering of the pistons, and I am therefore enabled to run them much faster, and consequently make a smaller machine answer for a given size of pipe.

I claim as my invention—

1. In a piston-meter, the combination of two pistons and the case having two independent piston-chambers, and a passage or passages leading from each chamber to a point in the other opposite the piston end when near the end of its stroke, said passages having a port at each end formed wholly in the cylindrical walls of said piston-chambers, the said pistons each having two portions which act alternately as valves to open and close said ports, whereby each of said pistons acts to cut off the water at each end of its own stroke, substantially as described, and for the purpose specified.

2. In a piston-meter, the combination of two pistons, a shaft and cranks for determining the stroke of said pistons, and the case having two independent piston-chambers, and a passage or passages leading from each chamber to a point in the other opposite the piston end when near the end of its stroke, said passages having a port at each end formed wholly in the cylindrical walls of said piston-chambers, the said pistons each having two portions which act alternately as valves to open and close said ports, whereby each of said pistons acts to cut off the water at each end of its own stroke, substantially as described, and for the purpose specified.

EDWARD C. TERRY.
